DISPENSING CONTAINER

Theodore P. Jakubowski, Clifton, N.J., assignor to Shulton, Inc., Clifton, N.J., a corporation of New Jersey

Application October 18, 1957, Serial No. 691,006

1 Claim. (Cl. 15—137)

The present invention relates to containers for dispensing materials, such as creams, pastes and salves or the like, and, more particularly, to an improved screw operated piston assembly for expelling the materials from the containers.

Heretofore, a great number of different arrangements have been proposed for expelling such materials from containers to dispense the same, but all of these have been objectionable for one reason or another, primarily because of cost and difficulty of manufacture and assembly.

Accordingly, an object of the present invention is to provide a dispensing container of the foregoing type which is not subject to the foregoing difficulties and disadvantages.

Another object is to provide such a container which is constructed of a minimum number of parts adapted to be assembled in a rapid and simple manner.

A further object is to provide such a container which functions better than those proposed before and will therefore appeal to the users thereof, whereby the sales of materials packaged in such containers will be increased.

Other and further objects will be obvious upon an understanding of the illustrative embodiment about to be described, or will be indicated in the appended claim, and various advantages not referred to herein will occur to one skilled in the art upon employment of the invention in practice.

A preferred embodiment of the invention has been chosen for purposes of illustration and description and is shown in the accompanying drawing, forming a part of the specification, wherein:

Fig. 1 is an elevational view of a dispensing container in accordance with the present invention with the closure for the dispensing head shown in longitudinal section.

Fig. 2 is a plan view of the container with the closure removed.

Fig. 3 is a sectional view taken along the line 3—3 on Fig. 2.

Fig. 4 is an elevational view of the piston, screw unit and mounting assembly apart from the container.

Fig. 5 is a sectional view taken along the line 5—5 on Fig. 3.

Fig. 6 is a sectional view taken along the line 6—6 on Fig. 3.

Fig. 7 is a bottom view of a disc for mounting the screw unit.

Fig. 8 is an enlarged fragmentary sectional view illustrating details of the container at the lower end thereof.

Referring to the drawing in detail, a dispensing container is shown which generally comprises five parts, namely, a receptacle 10, a closure 11 for the receptacle, a piston 12 for expelling material from the receptacle, a screw unit 13 for operating the piston, and a disc 14 for mounting the screw unit in the manner described hereinafter.

The receptacle 10 is tubular, preferably having a cylindrical wall 15, and has a dispensing head 16 at the top thereof provided with discharge openings 17 and screw threads 18 (Figs. 1 to 3), and has an opening at the bot-

2

tom. The lower end of the wall 15 is stepped at the interior thereof to provide a seat 20 at the bottom and a converging face 21 spaced adjacently above the seat 20 (Figs. 3 and 8). The wall is further provided at the interior with a plurality of circumferentially spaced ribs 22 extending axially from the dispensing head to the face 21 (Figs. 3 and 5) and a groove 23 extending upwardly from the face 21 a short distance (Figs. 3 and 8).

The closure 11 comprises a cover portion 24 provided with means 25 on the underside for closing the openings 17, and a skirt portion 26 having threads 27 for cooperating with the threads 18 to secure the closure to the receptacle (Fig. 1).

The piston 12 is an inverted cup-shaped member having a screw threaded, central sleeve 28 and a pair of thin annular, spaced apart fins 29 at the periphery thereof for engaging the inside of the wall 15 and forming a seal between the piston and the wall (Figs. 3 and 4). The piston is formed of a yieldable material, such as a plastic resin of the polyethylene type, whereby the fins are readily deformable to provide a good seal and are deformed by the ribs 22 to prevent rotation of the piston with respect to the receptacle. These fins also are deformed by the face 21 to facilitate inserting the piston into the lower end of the receptacle (Fig. 8).

The screw unit 13 is constructed in one piece and is so shaped that it can be molded of any suitable plastic resin. As shown in Figs. 3 and 4, this unit comprises a shaft 30 screw threaded through the sleeve 28, a manually operable knob or hand wheel 31 at the lower end of the shaft, and a collar 32 spaced adjacently above the knob 31 having a tapered upper surface 33 for the purpose to be described hereinafter.

The disc 14 is constructed of relatively stiff, flexible material, such as plastic resin. The disc, as shown in Figs. 3, 4, 6, 7 and 8, comprises a central raised portion 34 formed with an aperture 35 for receiving the portion of the shaft between the collar 34 and the knob 31, slots 36 extending outwardly from the aperture 35 and a slit 37 extending from the aperture to the periphery of the disc to render the same expandable, an annular rim 38 for engaging the receptacle wall 15 between the seat 20 and the face 21 and an annular rib 39 disposed on the seat 20, whereby the disc serves to rotatably mount the screw unit on the receptacle.

A bearing for the screw unit is provided by forming a circular, central boss 40 on the upper surface of the knob 31 and forming a central, circular recess 41 at the underside of the disc 14 for receiving the boss.

Preferably, the upper surface of the knob 31 and the underside of the disc are spaced apart to prevent any binding therebetween. This is accomplished by providing a plurality of pins 42 between these surfaces, for example, on the underside of the disc. These pins are dimensioned to bias the portions of the disc surrounding its aperture 35 against the underside of the collar 32, whereby the screw unit and the disc are retained in assembly.

The dispensing container shown herein preferably is filled and assembled in the manner about to be described. The closure 11 is applied to the receptacle, as shown in Fig. 1, apart from the piston, screw unit and disc assembly, and the receptacle is filled with a desired amount of material to a level slightly above the upper end of the groove 23 to accommodate the shaft 30 when later placed in the material.

The shaft 30 of the screw unit is passed through the aperture 35 of the disc 14 until the face 33 of the collar engages the underside of the disc. Pressure is then applied and the face expands the disc sufficiently to enable the collar to pass through the apertures, whereby the aperture receives the portion of the shaft between the collar 32 and the knob 31 to retain the disc in

assembly. The shaft is now threaded through the piston 12 to position the latter, as shown in Figs. 4 and 8.

Adhesive is applied to the seat 20 and/or the rib 39 and the piston is forced past the face 21 to a point above the groove 23, as shown in Fig. 8. While this is being done, the groove vents the air in the lower portion of the receptacle to facilitate insertion of the piston. When the adhesive sets, the disc 14 is permanently secured to the receptacle and the container is ready for use.

In use, the closure 11 is removed and the knob 31 is rotated clockwise (provided a left-hand thread is utilized), whereby the piston moves upwardly and expels the material through the dispensing openings 17 onto the surface of the dispensing head 16 which can now be used as an applicator. After use the closure is replaced.

As the material is being consumed, the air space beneath the piston increases. However, the formation of a partial vacuum which might retard the piston is prevented because this space is vented through the slots 36, the slit 37 and the space provided by the pins 42.

From the foregoing description, it will be seen that the present invention provides a novel and useful container of the type which expels the contents by screw operated piston means and which is not subject to the prior difficulties and disadvantages. The parts of the container are readily fabricated in an economical manner and are easily assembled. Furthermore, the container is practical and efficient in use and for that reason appeals to the user.

As various changes may be made in the form, construction, and arrangement of the parts herein, without departing from the spirit and scope of the invention and without sacrificing any of its advantages, it is to be understood that all matters are to be interpreted as illustrative and not in any limiting sense.

What is claimed is:

A dispensing container comprising a tubular receptacle having a dispensing head with perforations at the top thereof and an opening at the bottom thereof, an in-

verted cup-shaped piston of yieldable material slidably mounted in said receptacle underneath material to be expelled from said receptacle, a pair of thin, annularly spaced apart fins on the periphery of said piston for engaging an inner wall of the receptacle to form a seal between said piston and said inner wall, an axially extending rib on said receptacle inner wall for engaging said fins to prevent rotation of said piston, a one-piece unit including a shaft screw threaded through said piston; a manually operable knob at the lower end of said shaft and a collar on said shaft spaced adjacently above said knob, a flat disc having a central aperture for receiving a portion of said shaft between said collar and said knob and having means rendering the same expandable adjacent said aperture to enable said shaft portion to be so positioned, an annular rim and rib on said disc fitting into said opening and being adhesively secured therein to rotatably mount said screw means on said receptacle, a plurality of pins on the underside of said disc for spacing said knob from said disc and thereby preventing binding therebetween, said dispensing head having an external wall diameter less than that of said tubular receptacle and having screw threads thereon, a shoulder on said receptacle formed by said dispensing head of lesser diameter, and a closure having means at the underside thereof for sealing said dispensing head perforations and having internal threads for mesh engagement with said dispensing head threads, whereby said closure may be turned tightly against said shoulder for further sealing the material within said container.
